UNITED STATES PATENT OFFICE

JOHN P. DUGGAN, OF LONG ISLAND CITY, NEW YORK

FLUID STRAINER

Application filed August 28, 1930. Serial No. 478,450.

This invention relates to improvements in fluid strainers, and has particular reference to a device for straining gasoline from its source of supply in the tank of a motor vehicle to the carburetor of the motor thereof.

The primary object of the invention resides in the strainer device arranged within the gasoline supply tank for preventing sediment which might accumulate within the tank from being drawn through the gas line to the carburetor which if drawn therein would tend to clog the supply line and carburetor, and if passed on to the cylinders of the motor, would cause loss of power thereof.

Another object of the invention is to provide a strainer device in which the gasoline is drawn from a point adjacent the top of the level of the liquid supply at all times, and which never permits the fuel contents of the tank to be fully exhausted, it being understood that any sediment in the tank tends to settle upon the bottom thereof, hence the liquid fuel covering the bottom of the tank and mixed with the sediment is never drawn to the working part of the motor fed thereby.

A further object of the invention is the provision of a strainer device in which the inlet end of the gasoline supply line is supported within the tank upon a float, so as to be supported just below the liquid level of the tank, and means for accommodating the raising and lowering of the float and for bracing the float against lateral movement during the swishing of the tank contents so as to avoid strains upon the working parts.

With these and other objects in view, the invention resides in the certain novel construction, combination and arrangement of parts, the essential features of which are hereinafter fully described, are particularly pointed out in the appended claims, and are illustrated in the accompanying drawings, in which:—

Figure 1 is a rear elevational view of a motor vehicle showing the gasoline supply tank in longitudinal section with my improved strainer device mounted therein.

Figure 2 is a bottom plan view of the strainer device per se.

Figure 3 is an enlarged fragmentary vertical sectional view through the liquid supply tank with parts of my invention broken away in section.

Figure 4 is a top plan view of the strainer device per se.

Referring to the drawings by reference characters, the numeral 10 designates the liquid fuel supply tank of a motor vehicle 11, and which is provided with the usual filling opening 12 through which the tank may be filled with gasoline or other liquid fuel. In addition to the usual filling opening, the top of the tank is provided with an opening 13 through which my improved strainer device now to be described is inserted into position within the tank and the said opening sealed in a manner to be hereinafter explained.

Bolted or otherwise secured to the tank 10 and covering the opening 13 is a cover or attaching plate 14, there being a gasket 15 between these plates and the tank for sealing the said opening against the entrance of air into the tank for leakage of the contents of the tank therethrough. An elbow 16 is connected to the upper side of the cover plate 14 through a coupling 17 and connected to the elbow 16 is a fuel supply pipe 17' which leads to the carburetor of the motor of the vehicle 11. Connected to the cover plate 14 and depending from the under side thereof is an elbow 18, the passage in the elbows 16 and 18 communicating so as to provide an uninterrupted passage from the fuel supply pipe 17' through the coupling 17 for a purpose which will be fully understood. Connected to the elbow 18 is one end of a flexible metal tube 19, the opposite end of the said tube being connected to one end of a short length of pipe or tubing 20 by means of coupling or joint 21, the opposite end of the tube 20 is bent at an angle and provided with an enlarged head 22, the end of the head being rounded and threadedly receiving an inlet nozzle 23, the open end of the nozzle being protected by a screen 24.

Associated with the nozzle 23 is a float member 25 constructed of cork or other like buoyant material, the same being provided

with a centrally located chamber 26 which communicates with the outer side of the float member through passages 27, the outer ends of the passages being covered by screens or the like 28. The chamber 26 opens both on the under side and the upper side of the float member 25, the lower side of the chamber being closed by a plate 29 and the upper side by a plate 30, the two plates being secured by bolts or like fastening elements. The plate 30 is provided with a centrally disposed opening 31 for the passage of the nozzle 23 and which opening is sufficiently large enough to permit of the free turning of the float upon the nozzle. By reference to Figure 3, it will be seen that this construction permits the nozzle end of the fuel supply pipe to extend within the chamber 26 of the float and be supported in a position slightly below the liquid level of the tank contents.

A pivot bolt 32 extends transversely through the head 22 of the pipe 20 and through aligned openings provided in socket members 33 respectively disposed on opposite sides of the pipe or tube 20. The socket members 33 are yieldingly held against opposite sides of the head 22 by a spring 34 mounted on the pivot bolt 32 which spring abuts one side of one of the socket members and a washer 35 fixedly connected to the extending end of the pivot bolt.

Extending into the respective socket members 33 are one end of brace rods 36, the said rods being disposed in converging relation with respect to each other while their opposite ends are bent at an angle to provide trunnions 37 which have their bearings in ears 38 extending downwardly from the underside of the cover plate 14 and which ears are respectively disposed on opposite sides of the elbow 18. The brace rods 36 are adapted to brace the pipe 20 during its vertical movement caused by the raising and lowering of the level of the liquid contents within the tank and by reason of the springs 34 the brace rods are permitted a limited spreading movement caused by any pressure exerted upon the float member 25 to move the same in a lateral direction. Any lateral movement of the float 25 is also compensated for by reason of the same being turnably mounted upon the nozzle 23, and which lateral movement may be caused by the swishing of the liquid contents of the tank during the travel of the motor vehicle.

From the foregoing description it will be seen that a fuel tank equipped with a strainer device of the type herein shown and described will eliminate the possibility of any sediment which might accumulate in the bottom of the tank from being drawn through the gas line 17 and to the carburetor of the motor vehicle. The nozzle 23 is always supported adjacent the top of the liquid level and cannot touch the bottom of the tank,

therefore a certain quantity of fluid will remain in the tank at all times, it being understood that any sediment or water which might enter the tank will remain therein and will not be drawn to the working part of the motor.

While I have shown and described what I deem to be the most desirable embodiment of my invention, I wish it to be understood that various changes in the construction may be resorted to if desired, and I do not limit myself to the exact structural details herein set forth, nor to anything less than the whole of my invention, limited only by the appended claims.

Having thus described the invention, what I claim as new and desire to secure by Letters Patent is:—

1. In combination with a liquid fuel supply tank, a float member within said tank having a chamber therein opening to the outside of said float member, a flexible supply pipe having its inlet end extending into said tank and terminating in said chamber, means for facilitating the vertical and lateral movements of said float member due to the changing of the liquid level in said tank, and brace means associated with the inlet end of said pipe and automatically adjustable to the vertical and lateral movements of said pipe.

2. A strainer device for liquid fuel tanks comprising a flexible pipe, an attaching plate to which one end of said pipe is connected, the other end of said pipe being angularly disposed, a float member having a chamber therein opening through to the outside of said float member, the angularly disposed end of said pipe extending into said chamber and being connected to said float member, sockets pivotally mounted on said pipe, and brace rods pivotally connected to said attaching plate and freely extending into said socket.

3. A strainer device for liquid tanks comprising a flexible pipe adapted to be fixedly connected at one end, a hollow float member having openings therein, the opposite end of said pipe extending into said float member and being turnably connected thereto, brace rods, and resilient connecting means between said brace rods and said pipe to facilitate lateral and vertical movements of said pipe and float member.

In testimony whereof I affix my signature.
JOHN P. DUGGAN.
